[57] **CLAIM**

The ornamental design for a jack bracket, as shown and described.

DESCRIPTION

FIG. 1 is an exploded, environmental perspective view of the jack bracket;

FIG. 2 is an environmental perspective view of the jack bracket assembled;

FIG. 3 is an enlarged top plan view;

FIG. 4 is a side elevation of the jack bracket. The opposite side elevation is identical;

FIG. 5 is a front elevation;

FIG. 6 is a rear elevation; and,

FIG. 7 is a perspective view.

The broken line showing of a Jeep in FIGS. 1 and 2 and the structure in FIGS. 3-5 is for illustrative purposes only and forms no part of the claimed design.
